UNITED STATES PATENT OFFICE.

TRAFFORD N. JAYNE, OF MINNEAPOLIS, MINNESOTA, ASSIGNOR, BY DIRECT AND MESNE ASSIGNMENTS, TO THE NATIONAL MEASURING BOTTLE STOPPER COMPANY, OF SAME PLACE.

DESIGN FOR A BOTTLE-STOPPER.

SPECIFICATION forming part of Design No. 34,481, dated April 23, 1901.

Application filed April 9, 1900. Serial No. 12,249. Term of patent 14 years.

To all whom it may concern:

Be it known that I, TRAFFORD N. JAYNE, a citizen of the United States, residing at Minneapolis, county of Hennepin, State of Minnesota, have invented and produced a new and original Design for Bottle-Stoppers, of which the following is a specification, reference being had to the accompanying drawings, forming part thereof.

Figure 1 is a perspective showing the device in the position it is held for use. Fig. 2 is a view of one side of the stopper. Fig. 3 is a view of the opposite side. Fig. 4 is an end view.

As shown in the drawings, the leading or material features of my design consist of an oval-shaped bulbous portion whose wall A at one end describes a broad downward curve and merges into the wall B, that is inwardly

inclined and unites with the tapering walls 20 C of a hollow bottle-stopper portion. The wall D at the opposite end of the bulbous portion describes a gradual inward curve approaching the opposite wall B in a substantially horizontal direction and then, making 25 a short turn, is outwardly inclined in a direction substantially parallel with the wall B and unites with the wall C of the stopper portion.

I claim as my invention—

The design for a bottle-stopper, substantially as shown and described.

In witness whereof I have hereunto set my hand this 2d day of April, 1900.

TRAFFORD N. JAYNE.

In presence of—

RICHARD PAUL,
M. C. NOONAN.
